[57] CLAIM

The ornamental design for a bottle with cap, as shown and described.

DESCRIPTION

FIG. 1 is a front elevational view of a bottle with cap showing my new design;

FIG. 2 is a rear elevational view thereof;

FIG. 3 is a top plan view thereof;

FIG. 4 is a bottom plan view thereof;

FIG. 5 is a side elevational view thereof, the opposite side being a mirror image thereto;

FIG. 6 is a sectional view taken along the line 6—6 of FIG. 2, and looking in the direction of the arrows;

FIG. 7 is a front elevational view shown with the cap omitted for clarity of illustration;

FIG. 8 is a rear elevational view of FIG. 7;

FIG. 9 is a top plan view of FIG. 7; and

FIG. 10 is a side elevational view of FIG. 7.
